UNITED STATES PATENT OFFICE

2,605,666

MAGAZINE SOCKET WRENCH

Gordon L. Jorgensen and Irvin A. Jorgensen,
Clarion, Iowa

Application November 9, 1950, Serial No. 194,774

1 Claim. (Cl. 81—124.1)

1

This invention relates generally to socket wrenches and in particular to a magazine socket wrench for removing and replacing nuts on vehicle wheel studs and the like.

Socket wrenches for removing the wheel holding nuts from automobiles generally retain only a single nut, so that the wheel nuts are usually removed separately, placed together on the ground, and then separately replaced in wheel holding positions. As a result considerable time and inconvenience is encountered in a wheel removing operation.

It is an object of this invention, therefore, to provide an improved socket wrench for vehicle wheel removing purposes.

A further object of this invention is to provide a magazine socket wrench having a socket portion rotatable on a stem member which is manually held against rotation by a handle.

Still another object of this invention is to provide a magazine socket wrench of a simple construction, economical to manufacture, and efficient in operation to store nuts concurrently with their removal, and to release the nuts concurrently with their replacement.

Further objects, features and advantages of this invention will become apparent from the following description when taken in connection with the accompanying drawing in which:

Fig. 1 is a perspective view of the magazine wrench of this invention showing the same in an inverted position;

Fig. 2 is a longitudinal sectional view of the wrench shown in Fig. 1; and,

Figs. 3 and 4 are enlarged detail sectional views as seen on the lines 3—3, and 4—4, respectively, in Fig. 2.

With reference to the drawing the magazine wrench of this invention is illustrated in Figs. 1 and 2 as including a longitudinally extended tubular member 10 having a magazine section 11 and a reduced bearing section 12. A transverse handle 13 is secured, as by welding, to the tubular member 10 at the junction of the sections 11 and 12.

The section 11 (Figs. 2 and 3) has the bore 14 thereof of a polygonal shape in transverse cross section to receive nuts 16, and to hold the same against rotational movement relative to the tubular member 10.

A stem 17, positioned within the tubular member 10, has a threaded section 18 in a concentrically spaced relation within the magazine section 11, and a shaft section 19 rotatably supported within the bearing section 12. The threads

21, on the threaded section 18, correspond to the threads in the nuts 16.

5 Rotatably positioned about the free end 22 of the tubular section 12 is a tubular rubber hand grip 23, having at its closed end 24 a fixed internally threaded ring shaped insert 26 which is threadably engaged with a threaded portion 27 at the terminal end of the shaft portion 19. The insert 26 is engageable with the end face 28 of the bearing section 12 to limit the axial movement of the hand grip 23 inwardly of the wrench.

10 A tubular insert 29 fixed at the open end 31 of the hand grip 23 is integrally formed with a pair of oppositely arranged spring fingers 32 (Figs. 2 and 4), which project outwardly from the open end of the hand grip. The fingers 32 are engageable with an annular shoulder 33, formed on the bearing section 12, to limit the axial movement of the hand grip 23 in an outward direction.

15 It is seen, therefore, that when the hand grip 23 is held in one hand, and the handle 13 is turned with the other hand, that the tubular member 10 is rotated about and relative to the stem member 17.

20 In the use of the wrench of this invention, when a nut 16 is to be removed from a stud (not shown) of a vehicle wheel, the nut is partially received within the magazine section 11 and with the hand grip 23 held in one hand, the handle 13 is manipulated by the other hand in a direction providing for the removal of the nut from the stud. Concurrently with its removal from the stud, the nut 16 is threaded upon the stem portion 18, as a result of the nut being rotated with the magazine section 11 relative to the stem portion 18. When the nut 16 is removed from the stud it is at the position A, shown in Fig. 2, and located within the magazine section 11.

25 The same procedure is followed for the removal of a second nut from a vehicle wheel. During the removal of the second nut, the first nut is threaded further upon the stem portion 18 so as to be at the position B, illustrated in Fig. 2, when the second nut removed is at the position A. Thus on the removal of successive nuts 16, the nuts are stacked in the order of their removal upon the stem portion 18, and within the magazine section 11.

30 In replacing the nuts 16 upon the wheel studs, the handle 13 is manipulated in an opposite direction, relative to its turning movement when the nuts were removed, so that a nut 16 at its position A is threaded upon a stud concurrently with the unthreading or release thereof from the

threaded portion 18 of the stem 17. It is apparent, that with the release of a nut 16 from the magazine section 11, that the next succeeding or following nut 16 is at a position for threaded engagement with a corresponding stud.

Although the invention has been described with respect to a preferred embodiment thereof it is to be understood that it is not to be so limited since changes can be made therein which are within the full intended scope of this invention as defined by the appended claim.

We claim:

In a magazine wrench having a longitudinally extended tubular member with an elongated nut engaging socket portion at one end thereof, a stem member within said tubular member rotatably supported within the other end of said tubular member, and having a section projected outwardly from said other end portion, with the section of said stem member within said elongated socket portion being threaded to threadably engage nuts received within said socket portion, means for holding said stem against axial movement relative to said tubular member, a manual

grip on said projected stem section to hold the stem for rotation of said tubular member thereon, and means for rotating said tubular member, whereby nuts rotated by said socket portion are concurrently threadably moved on said stem member longitudinally of said elongated socket portion.
